United States Patent Office

Des. 193,759
Patented Oct. 9, 1962

193,759

BEVERAGE DISPENSER

Clare E. Hodgman, Mamaroneck, N.Y., assignor to The Coca-Cola Company, Atlanta, Ga., a corporation of Delaware

Filed Feb. 21, 1962, Ser. No. 68,915

Term of patent 14 years

(Cl. D2—3)

FIG.1

FIG. 2

FIG. 1 is a perspective view taken from the rear and one side of a beverage dispenser embodying my new design;

FIG. 2 is a rear elevation view thereof;
 FIG. 3 is a front elevation view thereof;
 FIG. 4 is a side elevation view thereof; and
 FIG. 5 is a top plan view thereof.

I claim:

The ornamental design for a beverage dispenser, substantially as shown.
